CLAIM

The ornamental design for a safety gate wall mounting set, as shown and described.

DESCRIPTION

FIG. 1 is a perspective view of a safety gate wall mounting set, showing my new design;

FIG. 2 is a perspective view of the top part of one piece of the safety gate wall mounting set;

FIG. 3 is another perspective view thereof;

FIG. 4 is a front thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a perspective view of the bottom part of the safety gate wall mounting set;

FIG. 11 is another perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof; and,

FIG. 17 is a bottom view thereof.

The evenly spaced broken lines and un-tinted areas depict portions of the safety gate wall mounting set that form no part of the claimed design. The dot-dot-dash broken lines in FIG. 1 depict environmental subject matter that forms no part of the claimed design.
